UNITED STATES PATENT OFFICE.

JAMES G. BROPHY AND FRED A. MANAU, OF CHICAGO, ILLINOIS.

PHOTOGRAPHIC-SHUTTER-CONTROLLING DEVICE.

1,177,921.

Specification of Letters Patent.

Patented Apr. 4, 1916.

Application filed December 3, 1914. Serial No. 875,295.

To all whom it may concern:

Be it known that we, JAMES G. BROPHY and FRED A. MANAU, citizens of the United States, residing at Chicago, in the county of Cook and State of Illinois, have invented certain new and useful Improvements in Photographic-Shutter-Controlling Devices, of which the following is a description, reference being had to the accompanying drawings, forming a part of this specification, in which corresponding reference numerals in the different figures indicate like parts.

The object of our invention is to provide a simple, cheap and effective device for use upon photographic cameras to prevent double exposures and to enable the user to determine with certainty just what sensitive surfaces or elements have been exposed and what have not.

To these ends, our invention consists in providing means, in conjunction with any well known form of automatic shutter, whereby, after actuating the latter to make an exposure, it may be automatically locked and so maintained until released by the act of removing the sensitive surface from the exposing position and substituting another in its place.

In the example illustrated, we have shown what we regard as the preferable construction, the invention being applied to a well known form of automatic shutter of the iris type, in conjunction with a sensitized roll-film and the usual means employed for shifting it. Other well known forms of spring-actuated, trigger-controlled shutters, such, for example, as the "focal-plane", "drop" or "rotary" type, may be used, however, with the same or other means for presenting and shifting or changing the sensitized surface in conjunction therewith, and hence we do not wish to be limited to the specific form shown.

Referring to the drawings.—Figure 1, is a rear elevation, partly in section, taken upon the line 1, Fig. 2, viewed in the direction of the arrow there shown, of a folding camera embodying features of applicants' invention, a portion of the detachable back being broken away, Fig. 2, is a side elevation partly in section, said section being taken upon the line 2, Fig. 1, viewed in the direction of the arrow there shown, Fig. 3, is a side view of a lens and shutter case, together

with a portion of the film shifting mechanism, the gearing connected therewith and the telescoping shaft and connections interposed between said gearing and the shutter-case, Fig. 4, is an enlarged longitudinal sectional view of a portion of the telescoping shaft, Figs. 5, and 6, are sections taken upon the lines 5, and 6, respectively, Fig. 4, viewed in the direction of the arrows there shown. Fig. 7, is an enlarged elevation of a portion of the shaft actuated by the film-shifting mechanism, and the worm-gears connected therewith for driving the telescoping shaft, Fig. 8, is a section taken upon the line 8, Fig. 7, viewed in the direction of the arrow there shown, Fig. 9, is an enlarged front elevation of the lens and shutter case, a portion of the latter being broken away to show the trigger and the locking mechanism connected therewith, Fig. 10, is an enlarged front view of the stop or locking mechanism, a portion of the ratchet-wheel being broken away, to show the main locking-wheel behind it, Fig. 11, is a view partly in section, taken upon the line 11, Fig. 9, viewed in the direction indicated by the arrow there shown, and Fig. 12, is a perspective view of the pawl interposed between the trigger and ratchet-wheel, together with the retaining-spring therefor.

Referring to the drawings, 1, Figs. 3, and 9, indicate generally a well known form of lens and shutter-case adapted for the use of an ordinary spring operated shutter, not shown. Pivoted at 2, Fig. 9, to the rear wall 3, of the shutter case, is the usual shutter-releasing trigger lever or arm 3, also shown in Fig. 3, said arm being connected with a suitable shutter and held normally in the position shown in Fig. 9, by means of a spring not shown, in a well known way. Journalled upon a stud 4, Figs. 9, 10 and 11, which is tapped into the rear wall 5, of the shutter casing, is a ratchet-wheel 6, the teeth of which are adapted to be engaged by a pawl 7, pivotally connected at 8, Fig. 9, to the trigger 3. The free end of said pawl is provided with a laterally extended lug 9, which is adapted to contact with the ratchet teeth with which it is yieldingly held in engagement by means of a retaining-spring 10, one end of which is secured to the casing in any approved way, while the other is bent as shown at 11, so as to straddle the pawl,

thereby acting to hold the latter in engagement with the ratchet while permitting it to be reciprocated by the action of the trigger. A spring stop 6^a serves to lock the ratchet-wheel against backward movement.

Formed upon or rigidly attached to the back of the ratchet-wheel 6, and concentric with its axis, is a crown-toothed ratchet 12, Fig. 11, the teeth of which are adapted to be engaged by laterally extended counterpart teeth as shown, upon a mutilated-gear wheel generally designated by 13, a portion of the front face of which is shown in Fig. 10. Said gear is loosely mounted upon the 15 stud 4, with a space between it and the wall 5, of the casing, to permit a sufficient backward and forward movement of said gear to enable the ratchet-teeth upon the two wheels to slip past each other. A light 20 spring 14, also shown in Figs. 9 and 10, has one end attached to the casing by means of a screw 15, while the other end is interposed between the casing 5 and the gear 13, so as to bear against the rear face of the 25 latter to hold the teeth of the two ratchet-wheels normally in contact, the free end of the spring having an opening therein, as shown at 16 Fig. 11, to receive the stud 4. The gear-wheel 13, is provided upon its periphery, with a plurality of groups of triangular-shaped or pointed teeth 17, between which groups said gear is cut away to provide blank spaces 18. Said groups and spaces which are arranged to alternate 30 throughout the periphery of the wheel, are equal in extent and equi-distant from each other.

Mounted upon a short shaft 19, Figs. 10 and 11, is a locking and releasing pinion 20, 40 having teeth similar in form to the teeth 17, which they are adapted to engage, but so spaced or disposed with reference thereto as to increase the back-lash, so that said pinion while capable of driving its fellow may 45 serve as a lock therefor in the manner and for the purpose hereinafter described. A spring-stop, 20^a, is provided to lock said pinion against backward movement. The shaft 19 is extended rearwardly through and 50 is journaled in a bearing in the wall 5, of the shutter-casing and the usual "front-board" or wall 21, of the camera, also shown in Figs. 1 and 3, to which the lens and shutter-case as well as the forward end of the 55 bellows 22, should one be used, are attached. Rigidly attached to the rear end of the shaft 19, is one member 23, Figs. 1, 3, and 11, of a universal joint which is connected by means of the usual intermediate member 24, 60 also shown in Fig. 4, to a counterpart member 25. The latter is, in turn, attached to the end of a small shaft 26, arranged to telescope with a tubular shaft member or section 27, forming one of a plurality of 65 tubular telescopic members designated, in

the example shown, by 28, 29, 30 and 31 respectively, into the last of which is projected a small shaft 32, corresponding to the shaft 26. The tubes 28 and 30, correspond with each other in length and diameter and are adapted respectively to receive in their outer ends the sections 27 and 31, while the two are adapted to enter opposite ends of the middle section 29, which is made of sufficient length to receive them. We prefer to make the several shaft sections polygonal in cross section, to enable them to telescope with each other, while serving to rotate or be rotated by their fellows. The cross sections shown in Figs. 5 and 6, show the co-acting parts to be rectangular, but we do not wish to be limited to the cross sectional form shown, nor to any specific construction so long as they are free to telescope and are provided with means for preventing rotation one within the other.

The shaft 32, has its projecting end connected with a universal joint, generally designated by 33, Fig. 3, and corresponding in construction to that of the well known 90 type connected with the shaft 26. The member 34, of said joint, Figs. 3 and 8, is rigidly attached to a short, horizontal shaft 35, also shown in Figs. 1 and 7, which is supported in bearings in a stirrup 36, journaled upon and suspended from a horizontal shaft 37, Figs. 1, 3, 7 and 8, by means of bored suspending members 38, 38. The shaft 37, is arranged horizontally and has its ends journaled in bearings 39 and 40, respectively, Fig. 1, in the upper part of the main frame 41, to which the rear end of the bellows is attached, said shaft being within the inclosure formed by the bellows and frame and so placed as not to interfere with the action of the light rays as they pass from the lens to the sensitized surface. The stirrup bearing support 36, is placed as near to one end of the shaft as may be and the telescoping shaft is placed as near to the bellows as may be, so as not to obstruct said light rays.

Mounted upon the shaft 37, between the parts 38, 38, and rigidly secured thereto by means of a pin 41, so as to be rotated by said shaft, is a worm 42, adjusted to engage the teeth of a worm-gear 43, rigidly mounted upon the shaft 35. A spur-pinion 44, Figs. 1, 2 and 3, is keyed to the opposite end of the shaft from the worm 42, and is adapted to be driven by means of a spur-gear 45, rigidly mounted upon the usual short sleeve 46, within which the film shifting key 47, of well known construction, is slidably mounted. Said sleeve and key are provided with the usual operating thumb-piece 48, Fig. 1, and the usual clutch mechanism not shown, inclosed within a hollow disk-like casing 49, to prevent the key 47, from being rotated except in a forward direction. The 130

usual film-roller, one end of which connects with the key in a well known way, and the other with the bearing-stud 51, is not shown.

- The operation of the device is as follows:
- Upon actuating the trigger-arm 3, to open and close the shutter, the ratchet-wheel 6, is moved by the pawl 7 a distance corresponding to the length of one notch and is locked against reverse movement by the action of the spring stop 6^a. The crown-toothed ratchet-wheel 12, being rigid with the wheel 6, and the mutilated gear-wheel 13, having its ratchet teeth in normal engagement therewith, said gear is caused to be rotated a distance corresponding to one of the blank spaces 18, during which movement the locking and releasing pinion 20, being opposite said blank space, can exercise no influence upon it. As soon, however, as the end of one of said blank spaces is reached, the teeth 17, of the gear 13, are brought into engagement, as shown in Fig. 10, with the teeth upon the pinion 20, which are so formed by a slight difference in spacing so as to increase the back-lash, that the end of one of said latter teeth will bear against the face of one of the teeth 17 at substantially right angles thereto, and lock the gear wheel 13, against further movement, through the action of the trigger, until said gear is released by the rotation of the pinion 20, as herein after described. In other words, the pinion 20, constitutes a modification of one form of "Swiss-stop;" and by taking advantage of the fact that a large gear may be locked by a small one unless the pitch-lines are properly designed, while at the same time the conditions as to movement may be reversed if the small one be used as the driver, we are enabled to utilize the pinion 20, both as a locking and releasing member, according as it becomes the driven or driving element. It will be noted that the pinion 20 is connected through the telescoping shaft described, the worm-gears, shaft 37, and gears 44 and 45, with the film-shifting key. No movement of these members, however, is caused by the operation of the shutter inasmuch as a blank space 18, is brought opposite to the pinion 20, as a result of the trigger movement, and hence the shaft and train of gears remain stationary, while the trigger is locked against movement by the pinion 20. The operator, having made the exposure, at once turns the film-shifting key in the usual way until a new section of film is moved to an exposing position. In doing so, the train of gears, the shaft 37, and the telescoping shaft are moved accordingly, thereby actuating the pinion 20 in the direction of the arrow shown in Fig. 9, which in turn, being then in engagement with the teeth 17, causes the gear 13 to be rotated through one section or until the next blank space 18 is reached. This movement is intended merely as a releasing movement for the ratchet 6 and is made possible by the yielding of the light spring 14 and the slipping of the ratchet teeth of the mutilated gear upon their fellows formed upon the part 12. It is obvious from this construction that after the pinion 20 shall have engaged the last tooth of a given group or section and is opposite a blank space, its further rotation in the same direction will produce no result. Hence it is immaterial how many turns may be imparted to it in shifting a film provided that the gears shall be so timed that said blank space shall not be prematurely presented, but it is of course, essential that it should not be reversed. This contingency is provided for not only by the spring stop 20^a, but also by the clutch mechanism connected with the film operating key.
- It is intended that the gears 44 and 45 and the worm-gears 42 and 43, shall be regarded as merely illustrative and in order to adapt them to cameras of varying size, utilizing films of different lengths, said gears should be so varied and proportioned with respect to each other as to insure the complete transfer of a film before releasing the shutter, in order to prevent double exposure.
- From what has been stated it will be apparent that as a result of the exposure of a given film, the shutter will be automatically locked and that another exposure cannot be made until the exposed film is shifted and a new one brought into an exposing position. In other words, in each case the shutter and film must alternate in their action.
- The device is equally applicable to instantaneous "bulb" and "time" exposures inasmuch as in the latter the trigger is so set by the time controlling device as to prevent its full return after the first or shutter opening movement, and hence does not recede far enough to cause the pawl connected therewith to engage a new tooth upon the ratchet-wheel; thereby enabling the second or shutter closing movement of the trigger to be made regardless of the lock. In our invention we have taken advantage of this well known trigger movement and so far as the shutter *per se* is concerned, make no claim thereto.
- It will be apparent that the locking pinion will be withheld from backward movement by the intervening shaft and worm-gear which could not be actuated in a backward direction by power applied to the mutilated gear through the trigger.
- Having thus described our invention, we claim:
1. In a device of the class described, the combination with an automatic shutter and means for actuating the same, of a mutilated gear having toothed and blank spaces thereon, means in operative connection with said shutter actuating means for moving said gear a distance corresponding to the extent of a blank

space thereon to bring a toothed portion into engagement with a locking and releasing gear, a locking and releasing gear for engaging the teeth of said mutilated gear, the two being so formed and adjusted that the mutilated gear may be locked thereby against movement through the shutter actuating mechanism when the teeth are in contact but may be driven by said locking and releasing gear when force is applied to the latter, and film-shifting means in operative connection with said locking and releasing gear for actuating the same to move said mutilated gear until a blank space thereon is presented opposite to said locking and releasing gear.

2. A device for the purpose specified, comprising in combination, a shutter, tripping means for releasing the same, a rotary member actuated by said tripping means to be moved a predetermined distance with each shutter tripping action, a mutilated gear arranged to be moved a given distance with each movement of said rotary member, a rotary locking and releasing pinion having teeth formed to lock said mutilated gear when a toothed section of the latter is brought into contact therewith but adapted to act as a driver to rotate said mutilated gear, means for enabling said mutilated gear to be moved in one direction by said pinion without causing a movement of said rotary member, film-shifting means and means actuated thereby for rotating said pinion to unlock said mutilated gear.

3. A device of the class described, comprising in combination, a shutter, tripping means for releasing the same, a rotary member actuated by said tripping means to be moved a given distance with each shutter tripping action, a mutilated gear driven thereby, a locking and releasing pinion having teeth formed to lock said mutilated gear when a toothed section of the latter is brought into engagement therewith but adapted to act as a driver to rotate said mutilated gear, means for enabling said mutilated gear to be moved in one direction by said pinion without causing a movement of said rotary member, film-shifting means, means actuated thereby for rotating said pinion to unlock said mutilated gear and means for preventing a backward movement of said rotary member, gear or pinion.

4. A device of the class described, comprising, in combination, a shutter, tripping means for releasing the same, a pawl actuated thereby, a ratchet-wheel actuated by said pawl, a crown-toothed ratchet carried by said ratchet-wheel, a mutilated gear hav-

ing a counterpart crown-toothed ratchet, means for holding the counterpart ratchets in normal engagement while permitting the last named one to slip upon its fellow when driven by said mutilated gear, a locking and releasing pinion having teeth adapted to lock said gear when the teeth of the latter are brought into engagement therewith but adapted to act as a driver to rotate said mutilated gear, film shifting means and means actuated thereby for rotating said pinion in one direction only.

5. A device for the purpose specified, comprising in combination, a shutter, tripping means for releasing the same, a rotary member actuated by said tripping means to be moved a predetermined distance with each shutter tripping action, a mutilated gear arranged to be moved a given distance with each movement of said rotary member, a rotary locking and releasing pinion having teeth formed to lock said mutilated gear when a toothed section of the latter is brought into contact therewith but adapted to act as a driver to rotate said mutilated gear, means for enabling said mutilated gear to be moved in one direction by said pinion without causing a movement of said rotary member, film shifting means and a rotary shaft and gears interposed between said locking and releasing pinion and said film shifting means for actuating said pinion to unlock said mutilated gear.

6. A device for the purpose specified, comprising, in combination, a shutter, tripping means for releasing the same, a rotary member actuated by said tripping means to be moved a predetermined distance with each shutter tripping action, a mutilated gear arranged to be moved a given distance with each movement of said rotary member, a rotary locking and releasing pinion having teeth formed to lock said mutilated gear when a toothed section of the latter is brought into contact therewith but adapted to act as a driver to rotate said mutilated gear, means for enabling said mutilated gear to be moved in one direction by said pinion without causing a movement of said rotary member, film shifting means and a telescoping rotary shaft and gears interposed between said locking and releasing pinion and said film-shifting means for actuating said pinion to unlock said mutilated gear.
